[57] CLAIM

The ornamental design for a drapery work table, as shown and described.

DESCRIPTION

FIG. 1 is a perspective view of a drapery work table showing my new design;

FIG. 2 is a front elevational view thereof;

FIG. 3 is a top plan view thereof;

FIG. 4 is a rear elevational view thereof; and

FIG. 5 is a left side elevational view thereof, the side opposite being substantially similar thereto.

FIG. 1

FIG. 2

FIG. 5
